UNITED STATES PATENT OFFICE.

ISAAC WATSON MYERS, OF HAMILTON, ONTARIO, CANADA.

BOOT-STRETCHER.

SPECIFICATION forming part of Letters Patent No. 309,154, dated December 9, 1884.

Application filed October 3, 1883. (No model.)

To all whom it may concern:

Be it known that I, ISAAC WATSON MYERS, of the city of Hamilton, in the county of Wentworth, in the Province of Ontario, Dominion 5 of Canada, have invented certain new and useful Improvements in Boot-Stretchers; and I do hereby declare that the following is a full, clear, and exact description of the construction and operation of the same.

10 The invention relates to further improvements on my boot-stretcher for which Letters Patent of the United States were granted to me on the 24th day of January, 1871, No. 111,137.

15 My first improvement relates to forming and constructing the heel and skeleton frame in one entire piece, my former one having them in two pieces, which is objectionable. My said improvement causes the stretcher to be more simple and durable.

20 Second. An objection was held to the old stretcher in that the heel portion sometimes slipped up in the boot when the device was in operation; and my second improvement consists in forming a point on the outer end of the 25 worm-rack, and made to project through a corresponding opening in the end of the sliding heel-piece. In the operation of stretching a boot, as soon as the turning of the heel-stud commences, the said point projects outward 30 into the heel of the boot about to be stretched and holds the heel of the stretcher firmly in place while the operation of stretching is being accomplished. As soon as the stud is reversed, the said point is withdrawn, which allows the stretcher to be easily removed from 35 the boot.

Third. In my former device the worm-rack, operated by a worm at the heel portion, could not move as far in and out horizontally as I 40 would wish; and my third improvement consists in cutting a recess diagonally at a proper angle in the roof of the heel portion of the instep, and placing therein at the same angle the disk provided with a worm that meshes 45 into the worm-rack, by which one portion only of the worm is actuating the said worm-rack at once. The other portion not meshing into it is above its teeth, and consequently allows the rack more latitude to operate the sliding heel-piece.

Fourth. A slight improvement is made on

the position of the hinges for the wings or side pieces, the old ones being hinged too far forward, which restricted their length and expansion and consequent usefulness. My fourth 55 improvement consists in hinging the said wings opposite the heel-stud, by which the said wings or side pieces are rendered longer and more capable of their swell portions being pressed outward to better advantage. 60

Fifth. I construct the upper section or instep of the last and the top part of the heel-piece or roof of the worm-disk in one entire piece, with holes drilled in the same at the proper places for the screw-studs to project 65 through. In my former stretcher these parts were separate, with slots cut in the same for the two foot-screw studs to pass through, and which required a recess in each screw, which was objectionable. Instead of the said recess 70 in the screws, I now place a collar around each of said screws, which have a bearing on the inside of the slanting portion of the instep. This change makes the device more easy of manufacture as well as more substantial. 75

Sixth. In my former or first stretcher I employed two separate studs or bearings for the foot-screws—one on the under side of the upper section or instep, and one on the lower or skeleton portion. I now do away with the 80 upper stud, elongate the lower one, and drill two holes in it for bearings for both screws, which improves and strengthens the device. I also cast on the under side of the said instep or upper section two lugs or projections, between which the said stud rests to steady it 85 and strengthen the instep.

Seventh. To the under part of the instep-plate proper in my old device I constructed a hinged prop, which rested on the lower or 90 skeleton frame. I now do away with said hinged prop and construct a solid one cast on the instep-plate proper, and cause it to slide in a groove in the bottom of the skeleton. This prevents the prop from moving from side to 95 side while supporting the said instep-plate proper.

Eighth. In my former boot-stretcher I secured the toe part of the skeleton or lower portion of the last to the same part of the upper section or instep of the last by a screw. I now do away with this method of securing the 100

said parts together, and in lieu thereof I cast on the toe part of the instep a projection curved toward the point, and its lower end made to pass through an opening in the skeleton frame, which holds the two parts of the device sufficiently together to answer all purposes.

By reference to the drawings forming part of this specification it will be seen that Figure 1 is a side elevation of my improved boot-stretcher. Fig. 2 is a plan of the same with one of the side wings removed. Fig. 3 is a vertical longitudinal section. Fig. 4 is a plan with instep proper removed, also the side wings or plates and the upper section of the former broken to show the interior arrangement of the various parts. Fig. 5 is a plan of the under side of the worm detached that actuates the worm-rack and sliding heel-piece. Fig. 6 is a side view of the same.

Full particulars of the working of my first boot-stretcher may be seen by reference to my patent cited above, No. 111,137, dated January 24, 1871.

25 A is the metallic frame or skeleton forming the lower part of the last, and in which the heel or lower part form a solid part of it. Its central portion is provided with a stud, r, slanting upward toward the front, and having two holes drilled in it to receive the ends of the screws C and H, said screws being provided with collars s s, surrounding them and made to press against the standing portion of the instep G. The said screws also pass through the nuts I and C'.

30 B is a sliding heel-piece having its shank or inner end moving in a slot in the heel portions of the skeleton frame, and made to operate by a worm-rack, a, set longitudinally into it, and having its outer end pointed, as at t, Fig. 3, and made to pass in and out of the heel-piece B through the hole u, to hold the heel of the stretcher firmly in the boot as it is being stretched. The worm-rack is actuated by 45 means of the disk B', set on an incline in the diagonal recess v, and provided with a worm, a', as seen at Figs. 5 and 6, one portion only of which meshes into the said worm-rack and moves it when actuated by a socket-wrench placed on its shaft, which projects up through the heel portion of the device.

40 F F are the wings or side pieces, curved to the outline of the foot, and provided at their broadest part with an internal vertical rib, 55 F'. They are hinged at their rear ends to the center of the heel portion of the machine, by which means they are made longer and more capable of expansion at the opposite ends or swell portion.

50 By reference to my said former patent it will be seen that the instep and heel portions (marked G and A, respectively) are two separate pieces; but I now make them in one piece; and in my first patent the instep G is shown 65 fastened to the skeleton or base piece at the toe by a screw, e. This I do away with, and form a projection, w, cast on the under side

of the toe of the said instep portion, and allow it to pass down into and through an opening, x, made in the skeleton frame A. This device holds the parts together just as well as and is more convenient than fastening them by a screw, as formerly.

On my first boot-stretcher I constructed a hinged prop to the instep-plate proper, J, 75 which prop rested on the floor of the skeleton frame. By reference to Fig. 3 it will be seen that I now construct a solid prop, z, cast to the said instep-plate proper, J, and which passes through an opening in the plate G, and its 80 lower end rests in a groove of the skeleton frame, which keeps it in its place.

H is the screw which passes through the nut I for moving the wedge E, which presses out the side wings, F F.

C is the lower screw, passing through a nut, C', for pushing out the slotted toe-piece D, which slides in the forward part of the skeleton frame.

M is a screw which passes through a nut, L, 90 attached to the rear end of the instep-plate proper, J, and rests in the recess o of the most elevated portion of the instep G. By turning the said screw with a socket-wrench the instep-plate proper, J, may be raised to stretch 95 that corresponding part of a boot.

I' I' are the arms, whose front ends interlock with the wedge E, and having the nut I between their upper ends. Turning the screw H pushes the wedge forward and presses out 100 the side wings. By turning the screw C the toe-piece D is projected forward, it being connected to the nut C' by arms similar to those marked I'.

N are lumps or movable bosses, which may 105 be placed at different parts of the device, as may be found necessary to enlarge that part of the boot where growers of corns require it.

The screws are cut with left-hand threads, for convenience, and squared on their heads, 110 to be easily rotated by a socket-wrench.

It will be seen that the instep G, the skeleton frame A, and the side pieces or wings, F F, are all secured together at the center of the heel by the hinge-pins m, lugs being cast on 115 the whole of them to form the hinges, rendering the machine less complicated and easier made.

Having thus described my improvements, what I claim as my invention, and desire to secure by Letters Patent, is—

1. In a boot-stretcher, the combination of the instep G and heel portion, made in one piece, with the screws C H, worm-disk B', and pointed rack a, substantially as specified.

2. In a boot-stretcher, the combination of the worm-rack a, provided with a point, t, heel-piece B, inclined worm-disk B', and metallic frame A, substantially as specified.

3. In a boot-stretcher, the combination of the diagonal recess v in the heel portion of the instep G, the inclined disk B', worm a', and worm-rack a, to operate substantially as and for the purpose specified.

4. In a boot-stretcher, the combination of the wings or side pieces, F, and heel portions A', the former hinged at or about the center of the latter, substantially as and for the purpose specified.

5. In a boot-stretcher, the combination of the instep G, screws C H, and collars s s, substantially as and for the purpose specified.

6. In a boot-stretcher, the stud r, cast on the skeleton frame and made to pass up to the roof of the instep G, and steadied in place between the lugs y y, cast on the roof of said instep, as described.

7. In a boot-stretcher, the solid prop z, cast on the toe of the instep-plate proper, J, and made to slide in a groove in the bottom of the

skeleton frame, as and for the purpose specified.

8. In a boot-stretcher, a projection, w, cast on the instep G, and an opening, x, in the skeleton frame, by which, as the former enters the latter, the two parts are united, substantially as and for the purpose specified.

9. In a boot-stretcher, securing the instep G, the skeleton frame A, and wings or side pieces, F F, together by hinge-pins m at the center of the heel, substantially as and for the purpose specified.

ISAAC WATSON MYERS.
